(57) **CLAIM**

The ornamental design for a passenger seat partition, as shown and described.

DESCRIPTION

FIG. 1 is a front perspective view of an embodiment of a passenger seat partition.

FIG. 2 is a rear perspective view of the passenger seat partition of FIG. 1.

FIG. 3 is a front view of the passenger seat partition of FIG. 1.

FIG. 4 is a rear view of the passenger seat partition of FIG. 1.

FIG. 5 is a right side view of the passenger seat partition of FIG. 1.

FIG. 6 is a left side view of the passenger seat partition of FIG. 1.

FIG. 7 is a top view of the passenger seat partition of FIG. 1; and,

FIG. 8 is a bottom view of the passenger seat partition of FIG. 1.

The dash-dot broken lines immediately adjacent to shaded areas represent unclaimed boundaries of the claimed design. The remainder of the passenger seat partition shown in broken lines shows unclaimed subject matter only and forms no part of the claimed design.
